DEVICE FOR MENTHOLIZING CIGARETTES

Albert O. Walker and Carl James Sanford, Independence, Mo.

Application April 28, 1937, Serial No. 139,536

6 Claims. (Cl. 131—55)

This invention relates to the process and device for mentholizing or otherwise treating the tobacco in smoking articles, and is particularly suited for treating the tobacco in cigarettes and pipes with menthol or any other desirable volatile substance.

The principal object of the present invention is the provision of an article of manufacture, comprising a recessed bowl, with openings through the walls thereof, to communicate with said recess, and a hollow insert having its inner portion frusto-conical with an opening through the inner end thereof to communicate with a chamber formed between the bowl and the insert, and a volatile treating material in said chamber whereby when a stream of air is passed therethrough, it will be impregnated with said volatile material and then passed through the tobacco of a smoking article.

Another object of this invention is the provision of an article of manufacture, having a compartment for containing a volatile material, and having openings therein, whereby air may be directed through said chamber, thence through the tobacco of a smoking article.

A further object of this invention is the process of impregnating the tobacco contained within a smoking article with a volatile substance comprising passing a stream of air through a chamber containing a volatile substance, whereby said stream of air is impregnated, then passing said treated air through the tobacco of said smoking article, whereby said tobacco is impregnated with the volatile substance.

With these, as well as other objects which will appear during the course of the specification, in view, reference will now be had to the drawing, wherein:

Figure 1 is a front elevation of an article of manufacture, embodying this invention.

Fig. 2 is a rear elevation of the same.

Fig. 3 is a side elevation of the article, partially broken away, and with a cigarette positioned therein for treatment.

Fig. 4 is an edge view of the article, shown in position on the bowl of a pipe for treating the tobacco contained therein.

Fig. 5 is an enlarged, transverse, sectional view of the article.

Fig. 6 is an enlarged view of the recessed bowl, with the insert removed therefrom, and

Fig. 7 is an enlarged, inner face view of the hollow insert.

Throughout the several views, like reference characters designate similar parts, and the nu-

meral 10 indicates a recessed bowl which may be made of wood, hard rubber or any other material that will not be affected by the treating material to be used therein. As indicated in the drawing, the recess 12 formed in bowl 10 is preferably of cylindrical form and extends substantially through said bowl to present a wall 14. Openings 16 are formed through wall 14 adjacent the outer periphery of recess 12 to communicate therewith.

For convenience in manufacture and carrying in the pocket, the bowl is made circular in form, with rounded edges. A hollow insert 18, provided at its outer portion with a cylindrical surface 20, is adapted to snugly fit into recess 12 and retain its position therein under all normal conditions. The inner portion 22 of insert 18 is frusto-conical in shape and provided at its central portion with an opening 24, which communicates with recess 12 through transverse grooves 26.

Referring to Fig. 5, it will be noted that the insert 18 is fitted into the recess 12 of the bowl until the inner end of 18 rests against the inner surface of wall 14, and due to the shape of the inner portion of the insert, an annular chamber 28 is formed between the bowl and the insert. This chamber is adapted to receive a fibrous or otherwise porous material which is suitable for carrying a volatile material, such as menthol crystals, so that as air is forced through openings 16, thence through the chamber 28 wherein the volatile material is lodged, the air will become impregnated with said volatile material and then pass through grooves 26, opening 24, and into the tobacco T of a cigarette C or pipe P when they are positioned respectively as shown in Figs. 3 and 4.

Materials other than menthol crystals, such as camphor, peppermint, etc., might also be used in this article for treating the tobacco to be smoked.

In the carrying out of this process by means of the article as described, it will first be considered that a cigarette is to be treated, and in such cases, the cigarette C is positioned as shown in Fig. 3, with one end thereof resting against the frusto-conical wall 30. The operator may now blow through openings 16 to force air through the chamber 28, thence to grooves 26, opening 24 and into and through the cigarette C, thereby depositing a portion of the volatile material in the tobacco T. For varying the quantity of the volatile material to be deposited in the tobacco, a variable amount of air may be passed through

the cigarette. Also, the operator may reverse the process by placing the cigarette in the mouth and sucking the air through in like direction as it was forced through by blowing.

5 Referring to Fig. 5, where the article is to be used for treating the tobacco in a pipe, it will be observed that the outer portion of insert 18 extends beyond the bowl 10, thereby presenting a shoulder 32, which serves for centering the 10 article on the pipe so that the operator may either blow or draw the air through the tobacco as described above.

This article is made of convenient size and form so that it may be carried in the pocket and 15 used many times without refilling.

What we claim is:

1. An article of manufacture comprising a recessed bowl having openings formed therethrough communicating with said recess; a hollow 20 low tapered insert, having an opening through the center thereof, and adapted to be fitted into the recessed bowl to form a chamber therebetween; and a fibrous medicated filler in said chamber formed between said bowl and insert, 25 whereby air passing therethrough will be impregnated by any material suspended in the filler.
2. An article of manufacture comprising a bowl having a cylindrical recess formed therein and 30 having openings formed through the wall thereof to communicate with said recess; a hollow insert, having its inner end frusto-conical in shape and having an opening through its central portion, adapted to be securely fitted into said recess to produce a chamber therebetween; and a porous medicated filler in said chamber whereby air passing through said chamber will be 35 impregnated with any material suspended in the filler.
3. An article of manufacture comprising a bowl having a cylindrical recess formed therein and 40 having openings formed through the wall thereof to communicate with said recess; a hollow insert, having its inner end frusto-conical in shape and having an opening through its central por-

4. An article of manufacture comprising a bowl having a cylindrical recess formed therein and having openings formed through the wall thereof to communicate with said recess; a hollow insert, 5 having its inner end frusto-conical in shape and having an opening through its central portion, adapted to be securely fitted into said recess to produce a chamber therebetween; and a porous medicated filler in said chamber whereby air passing through said chamber will be impregnated with any material suspended in the filler.

6. An article of manufacture comprising a bowl having a recess formed therein and openings through the wall of said bowl to communicate with said recess; an insert having a center opening formed therethrough, adapted to co-operate with said bowl to form a compartment for the 40 reception of a volatile material; and a recess formed in said insert for the reception of the end of a cigarette above said center opening.

ALBERT O. WALKER.

CARL JAMES SANFORD.
